(57) CLAIM

I claim, the ornamental design for a sprayer for a bottle, as shown and described.

DESCRIPTION

FIG. 1 is a front perspective view of a sprayer for a bottle showing my new, original and ornamental design;

FIG. 2 is a rear perspective view thereof;

FIG. 3 is a front view thereof;

FIG. 4 is a rear view thereof;

FIG. 5 is a side view thereof, taken from the right of FIG. 3, the opposite side being a mirror image thereof;

FIG. 6 is a top view thereof; and,

FIG. 7 is a bottom view thereof.
